MANIFOLDING APPARATUS FOR TYPE-WRITING MACHINES

Claude Wellington Brumhill, Leicester, England,
assignor to The Imperial Typewriter Company,
Limited, Leicester, England

Application February 24, 1943, Serial No. 476,970
In Great Britain November 27, 1942

8 Claims. (Cl. 197—126)

This invention comprises improvements in and relating to manifolding apparatus or attachments for typewriting machines and relates to that kind of apparatus that is intended for the production of a plurality of carbon copies by employing a plurality of plies of continuous stationery interleaved with carbon sheets or transfer material and comprises a carbon support trolley or the like (hereinafter referred to as a trolley) movable towards the typewriting mechanism in typewriting and away from the said mechanism e. g. to retract the carbons between the plies of stationery, and a track on which the trolley moves. Such apparatus is hereinafter termed "of the kind referred to," and is commonly constructed as an attachment to be attached to the rear of a typewriter.

In apparatus of this and somewhat similar kinds, various arrangements for the retraction of the trolley have been proposed or put into practice. In one arrangement, the trolley is pushed back by hand while in the other hand the operator grasps the front edge of the paper web. In others, the advance of the trolley as the paper and carbons are fed forward by the platen stores up energy in a spring which is subsequently released to retract the trolley, with the web and carbons, the trolley being then locked in its rear position while the web is pulled forward by hand.

The present invention is primarily concerned with improved arrangements for the retraction of the trolley and as viewed from one aspect provides manifolding apparatus of the kind referred to, having spring return mechanism for retracting the trolley, and means for winding up said mechanism at the termination of the forward travel of the trolley. This arrangement therefore obviates the trolley being drawn forward against the pull of the return mechanism. It is especially applicable to typewriting machines having a platen displaceable between operative and inoperative positions, and as viewed from another aspect the invention includes the combination, with such a machine, of manifolding apparatus of the kind referred to, having spring return mechanism for retracting the trolley, and means for winding up said mechanism in displacement of the platen to its inoperative position at the termination of the forward travel of the trolley. Thus, particularly in the case of a machine in which the platen is displaceable manually, there may be an operating connection between the platen displacing means (e. g. a displaceable sub-frame carrying the platen) and the spring mechanism so that the act of displacing the platen winds up the spring mechanism. The expression "wind up" is employed herein in a broad sense to include the act of stressing or loading the spring mechanism. The latter preferably includes a coil spring which

may be a tension spring or a compression spring, although an elastic cord or the like may be employed.

For reasons that appear hereinafter, it is further preferred that the arrangement shall be such that the spring effort is not applied to the retraction of the trolley until a predetermined stage in the displacement of the platen. A further feature of the invention resides in the provision of 5 means whereby, for equal distances of travel of the trolley the applied spring force is kept substantially constant.

These, and other features of the invention set out in the appended claims, are incorporated in the construction which will now be described as 10 an example with reference to the accompanying drawings, in which

Figure 1 is a plan of the relevant parts of the apparatus;

20 Figure 2 is a side elevation thereof;

Figure 3 is a plan, partly in section, of a portion of the apparatus with the cover plate hereinafter referred to removed;

Figure 4 is a plan showing certain details of the 25 mechanism shown in Figs. 1-3, and draw band clutch release mechanism;

Figure 5 is a sectional elevation of certain of the mechanism, looking forward towards the typewriter carriage;

30 Figure 6 is an underneath view of the draw band clutch-release mechanism shown in Figs. 4 and 5.

Figure 7 is a further detail of said mechanism looking from the rear;

35 Figure 8 is a sectional elevation showing an adjustment for the draw band;

Figure 9 is a side elevation, showing a safety 40 catch mechanism, for the carbon trolley, in the attitude occupied by it when the draw band clutch is engaged and the carrier blades not in position;

Figure 10 is a like view showing the catch mechanism when the carrier blades are in position;

Figure 11 an opposite side elevation, partly in 45 section, corresponding to Fig. 9, but with the draw band clutch disengaged;

Figure 12 is a side elevation of adjustment mechanism for adjusting a back stop for the trolley;

50 Figure 13 shows said back stop;

Figure 14 is an elevation of a part of a release rail for the trolley.

The invention is illustrated as applied to a manifolding attachment of the kind (of which 55 that described in British patent specification No. 548,199 is one example) comprising a carbon trolley 20 mounted by means of wheels 21 to travel on tracks 24 of a frame (indicated generally at 22) towards and away from the typewriter carriage 23; the said frame 22 is itself

attached to the rear of the carriage 23 to travel therewith, and for this purpose is supported by means of wheels 25 on a track 26 of a support frame generally indicated at 27 and which is conveniently attached to the rear of the typewriter itself. The details of this frame 27 are not important to the invention; the frame 22 may comprise longitudinals 22a—22b and cross members 22e, 22f. The carbon trolley 20 carries carbon blade supports 28 in which carbon blades 29 may be releasably mounted and for particulars of one construction of carbon support reference may be made to the aforesaid patent specification. As is well known, as typing proceeds the interleaved carbons and plies of paper are fed round the platen 30 and the carbon trolley 20 is therefore drawn forward towards the carriage. When the requisite length of typing has been effected the edge of the paper comes against a paper stop 33 on the paper support arm 34. By gripping the top edge of the paper against said support arm 34 the said arm is pulled forward, releasing the platen locking mechanism 121 (which may be as described in British patent specification No. 548,198), so that the platen sub-frame 31 is swung about its pivot 32 until the platen 30 occupies the position shown in chain dotted lines in Fig. 2. The carbon carriage 20 is then retired, drawing the carbons rearwardly between the plies of paper, the platen is restored to its operative position, and the typed sheets of paper are torn off so that typing may be recommended. The present invention is concerned with mechanism for retiring the carbon trolley 20.

Connected to the platen sub-frame 31 at 35 there is a rearwardly-extending arm 36 terminating in a rack 37 which engages a pinion 38 on a cross shaft 39 which is suitably supported in bearings on the frame 22. This shaft 39 further carries a drum 40 to which a metal draw band 41 is attached, the free end of this band 41 being attached to a slider 42 which is mounted to slide on a track member 43 extending centrally of the frame 22, the said slider 42 being biased towards the rear by a light tension spring 44 so as to take up slack in the band. The said track member 43 also supports two slidable members 45 and 46 that are connected by a pair of tension springs 47, the member 46 being biased forwards by light tension springs 48 anchored to the frame 22 at 49. It will therefore be seen that when the platen 30 is raised to an inoperative position the shaft 39 and drum 40 are rotated to wind up the band 41 and to draw the slider 42 forward. The said slider 42 contacts the member 45 and tends to tension the springs 47. The member 46 is connected to the carbon trolley 20 by an arrangement whereby the said spring tension urges the trolley rearwards to draw the carbons back between plies of paper. For this purpose said trolley 20 has connected to it at 50 a cord 51 or other flexible member which passes over a pulley or like system and has its other end connected to an anchorage 52 on the frame 22. The said pulley system is clearly shown in Fig. 3. It will be seen that from the point 50 at which it is attached to the trolley 20 the cord 51 extends rearwardly to a pulley 53 on frame 22, then forwards to pulley 54 on slidable member 46, rearwardly to pulley 55 on frame 22, forward to a second pulley 56 on member 46, and then rearwardly and around pulleys 57 and 58 on frame 22 and thence to the anchorage 52. From this arrangement it will be appreciated that when the springs 47 are tensioned and the mem-

ber 46 is drawn forward thereby the trolley 20 is drawn to the rear.

It is desirable, however, to provide means whereby the trolley 20 is prevented from moving towards the rear until the platen 30 has been raised sufficiently that undue friction will not occur between the carbons and paper and until the springs 47 have been tensioned to an adequate extent. For this purpose there is a rack 59 (Figs. 1 and 5) extending lengthwise of the frame 22 and conveniently formed in a cover plate 60 concealing the springs 47, the pulley system, and associated parts, and with this rack 59 a releasable gravity pawl 61 on the trolley 20 co-operates, the arrangement being such that as the trolley advances the pawl 61 clicks over the rack 59 and prevents rearward movement of the trolley until it is released. This release is effected by means of a lifting finger or cam 62 on shaft 39 which, at the appropriate stage, makes contact with a release rail 63, hereinafter described in greater detail, which rail co-operates with a roller 64 on the pawl 61 and lifts the latter out of engagement with the rack 59. This rail 63 extends lengthwise of the frame 22 and is attached to frame member 22c by means of screws 65 that extend through slots 66 in it (Fig. 14). Therefore irrespective of the position occupied by the trolley 20 at the termination of its forward advance, the pawl 61 will be raised at a predetermined point in the release movement of platen 30.

For convenience in setting up the machine it is necessary to disconnect the springs 47 and to provide for a "free" trolley. The drum 40 is slidable along shaft 39 against the action of a compression spring 80 to disengage a dog clutch 81 whereby it is normally clutched to the shaft. This clutch release is effected by means of a push rod 82 which extends through suitable bearings on the frame 22, and at one end engages a flange of the drum 40 and at the other end is provided with a push button 83. When pushed in the rod releases the dog clutch 81. It also rocks, by means of a collar 84, a bell-crank-lever 85 pivoted at 86 to the frame 22 which bell-crank-lever thereupon raises the release rail 63 and releases the pawl 61. The said pawl 61 is provided with a platform or lip 61a which extends underneath one arm 87a of a three-armed lever which is pivoted at 88 on the detachable head 20a of the trolley 20. A further arm 87b of the said lever normally projects above the surface of the trolley, while the third arm 87c overlies the rear end of a stop pawl 89 which is pivoted to the trolley 20 at 90. Normally a spring 123 causes the stop pawl 89 to engage with the rack 59, but when the clutch release rod 82 is pushed inwards to release the clutch 81 and pawl 61 is released as shown in Fig. 11. Means are provided for retaining the clutch 81 in the free position. To this end the release rod 82 has a block 91 (Figs. 5, 6, and 7) attached to it and is biased in the anti-clockwise direction (looking on the outer end of rod 82) by a tension spring 92 extending between a projecting rod 93 on said block and a plate 94 attached to the frame 22. The said block 91 is provided with a slot 95 for the reception of a dog 96 attached to said part 94, while at the right-hand side of said slot 95 there is a short recess 97. Therefore, when the clutch release rod 82 is pushed in, the block 91 disengages from the dog 96 and said block and rod are rotated by spring 92 until the dog 96 engages in the recess 97; the rod 82 is then held

in the free position, and it may here be mentioned that the drum 40 is prevented from rotating under the influence of take-up spring 44 by the engagement of a pin 98 projecting from it with an abutment 99 on the frame 22. When it is desired to engage the clutch the knob 86 and rod 82 are turned in the clockwise direction to align the dog 96 with the slot 95 and the compression spring 80 thereupon moves the drum 40 and not only engages the dog clutch 81 (already correctly positioned for engagement by members 98, 99) but also moves the release rod 82 to the left in Figs. 5 and 6, and engages the dog 96 in the slot 95.

It is desirable that some kind of tell-tale shall be provided so that the operator can readily see whether the rod 82 is in the release position. For this purpose there is a member 100 which freely encircles the rod 82 between the block 91 and a collar 101 so as to slide with the rod. The said member 100 is prevented from rotating with the rod by means of a screw 102 which extends through a slot 103 into a part of the frame 22, and is provided at the top with an overturned lip 100a which travels beneath a hole 104 in a small cover plate 105 and is coloured in two different colours so that according to whichever colour appears beneath the hole 104 the operator may know the position of the clutch release rod 82.

It may here be mentioned that it is impossible to push the rod 82 inwards to release the clutch 81 when the platen 30 is raised. Fig. 2 shows that when the platen is in the raised position a part of the rack 37 is brought nearer to the centre of rod 82 than when the platen is in its operative position. This part of the rack co-operates with a collar 114 on rod 82 and prevents the rod being pushed in, whereas when the platen is in operative position the rack is sufficiently spaced from rod 82 to permit the passage of collar 114.

The illustrated arrangement of pulleys ensures that the spring force tending to return the trolley 20 is proportional to the length of travel of the trolley. It will be noticed from Fig. 3 that with the trolley in the rearward position there is a space between slider 42 and member 45. As the trolley travels forwards, the member 45 moves back in the ratio 4:1 and reduces the gap. Hence, the nearer to the carriage 31 is the forward limit of travel of the trolley 20 the less is the idle motion of the slide 42 (when drawn forward by the act of raising the platen 30) before it contacts member 45 and greater is the tension imparted to springs 47.

The length of the forms or the like to be typed is usually such as to necessitate the trolley travelling over only a portion of the distance afforded by tracks 24. In such case it is usual to commence with fairly long carbons, and to have the trolley 20 utilising a rearward portion of its permissible travel. As typing proceeds the carbons wear, and therefore, the operator periodically tears a strip off the front end thereof, thus progressively shortening the carbons and causing the trolley 20 to utilise portions of its track that are progressively nearer the carriage 31. Since the members 45, 46 are connected to the trolley 20 in such manner that as the latter moves forward said members are moved back, unless precautions are taken this would result in the spacing (shown in Fig. 3) between member 45 and slide 42 decreasing, thereby decreasing the idle motion of the slide 42 before it contacts member 45 and applies tension to springs 47, with

the further result that the spring force is progressively increased as the carbons are shortened and the trolley 20 uses portions of its track that are progressively nearer the carriage. It will therefore be appreciated that it is desirable so to arrange matters that, irrespective of the portion of the track over which the trolley moves (or, as viewed from an analogous aspect, irrespective of the rear limit of travel of the trolley), for equal distances of travel of the trolley the spring force shall be kept substantially constant or shall not unduly increase.

In order to overcome these difficulties the anchorage 52 of the cord 51 is adjustable, so that by moving said anchorage 52 towards the rear of the frame 22 the members 45, 46 are permitted to move forward under the influence of tension springs 48. For this purpose the said anchorage 52 is slidable along a strip 67 (Figs. 3 and 12) attached to frame member 22a and pierced with holes 68 in which a plunger 69 incorporated in said anchorage 52 may be selectively engaged. This adjustment is also employed to adjust a back stop 70 for the rearward limit of travel of the trolley 20. The said anchorage 52 has connected to it, at 71 and 72, the two ends of a cord 73 which extends in two laps between pulleys 74 and 75 at opposite ends of frame 22, one of which laps carries the stop 70. In advance of the stop 70 there is preferably a cushioning spring 76 on the cord 73 with which spring an abutment 77 (Fig. 13) on the underside of the trolley 20 cooperates.

Means are provided for adjusting the tension to be exerted by the springs 47. This adjustment is shown in Figs. 2 and 8. The draw band 41, which has one end secured to the slider 42, has its other end secured to the drum 40 at 106 but has a loop indicated at 41' in Fig. 8 passing round a pulley 107 mounted in a cradle 108 that is adjustable along a track 109 on a frame member to which the track 43 is connected. Obviously by adjusting the cradle 108 the size of the loop 41' is adjusted and the spacing between the slider 42 and the spring anchorage member 45 is increased or decreased. The adjustment is effected by a lead screw 110 which screws through a part 108' of cradle 108 and is located by means of a nut 111 and a knurled nut 112 on opposite sides of a downward extension 109' of the track 109. By rotating the knurled nut 112 the lead screw 110 is rotated. The latter is provided with two lock nuts 113 so that if desired it may be locked in any position, and the extent of the adjustment is indicated by a pointer 122 on the frame 22 which co-operates with plus and minus signs on the cradle 108.

In setting up the manifolding apparatus the push button 83 is pushed in to the free carriage position and the web of paper is brought forward over the support rail 115 at the back of the frame 22 and is fed under the platen 30 as far as the tearing off knife 116. The paper is then clamped in position at the back of the frame by means of a clamp arm 117 projecting from one of the two guide plates 118 which plates are frictionally mounted so as to be rotatable and slidable along the support rail 115. The paper being thus secured, and slidable paper guides 119 at the front of the frame 22 and the guides 120 on the trolley 20 having been adjusted (the latter by screw means 120a and slots 120b), the paper support arm 34 is swung forward to the substantially horizontal position shown in dotted lines in Fig. 2, in which the platen 30 is raised.

The front end of the paper is thus freed from the platen, and the carbon blades 29 with their attached carbons are then inserted starting with the lowermost blade, and it will be appreciated that when the lowermost blade 29 is placed in position it depresses the lever arm 87b as shown in Fig. 10 so that when at a still subsequent stage the release rail 63 is lowered the safety pawl 69 is held disengaged from the rack 59. The carriage 20 is then so adjusted and the back stop 10 15 20 set by means 69 that the front edges of the carbons are located at the appropriate distance short at the front edges of the paper, leaving the requisite margin for the thumb grip. Next, the platen is lowered, the clamp 117 is released 15 and the paper is fed round the platen to the typing position and the push button 83 is turned so that the rod 82 springs outwards and the dog clutch 81 is engaged. This movement of the rod 82 likewise lowers the release rail 63 and permits the gravity pawl 61 to descend. Typing may therefore proceed until the front edge of the paper comes against the adjustable paper stop 33 on the paper support arm 34. With the right hand the operator then grasps the top margin of the paper against said arm 34 and swings the latter forward as in Fig. 2. During this movement the drum 40 is rotated and the springs 47 are tensioned until at the appropriate stage the cam 69 causes the release of the pawl 61 so that the carriage 20 is retired to the position set by 25 30 35 the back stop 70, drawing the carbons rearwardly for the appropriate distance between the plies of paper. The platen is then lowered to the operative position, the typed forms or the like being torn off the web of paper against the knife, and the next batch of typing may be commenced.

It may here be pointed out that since the position of the paper stop 33 on the paper support arm 34 is determined by the length of typing, the leverage afforded by said arm for raising the platen and for tensioning the springs 47 is proportionate to the distance through which the carbons have to be retracted and to the degree to which said springs are tensioned to effect said retraction. It may also be pointed out that it is desirable so to arrange matters that, in the raised position, the weight of the platen and paper support arm balances the pull exerted on the rack 30 by the springs 47.

The cord 51 may be any flexible member and pulleys 53-58 are illustrated as one example of suitable guides for said flexible member.

I claim:

1. In combination with a typewriting machine having a platen displaceable between operative and inoperative positions: manifolding apparatus comprising a carbon support mounted for movement toward and away from the platen; means for moving said support toward the platen; spring mechanism for retracting the support from the platen; means for winding up said mechanism in the displacement of the platen to its inoperative position at the termination of the forward travel of the support; and means for delaying the application of the spring effort to the retraction of the carbon support until the platen reaches a predetermined stage in its travel to inoperative position.

2. Manifolding apparatus for a typewriter machine having typewriting mechanism, which apparatus comprises a carbon support movable toward and away from the typewriting mechanism, a track on which the support travels, spring return mechanism for retiring the support from the typewriting mechanism, means for loading the spring mechanism at the termination of the forward travel of the support, a catch for preventing the application of the spring effort to the return of the support while the spring mechanism is being loaded, and release means, associated with the loading means, for releasing said catch.

3. The subject-matter of claim 2, having said catch arranged to hold the support in its forward position.

4. The subject-matter of claim 2, having a rack extending lengthwise of the track, a pawl engageable therewith for holding the support at its forward extremity of travel, and a pawl release, associated with the loading means, for releasing the pawl.

5. The subject-matter of claim 2, having a rack extending along the track, a pawl on the support engageable with the rack to hold the support at the termination of its approach to the typewriting mechanism, a pawl-release member extending lengthwise of the rack for releasing the pawl whatever the terminal position of the support, and means for operating said member to release the pawl at a predetermined phase.

6. In combination with a typewriting machine having a platen displaceable between operative and inoperative positions: manifolding apparatus comprising a carbon support movable toward and away from the platen; a track upon which said support travels; means for moving the support toward the platen; spring mechanism for retracting the support from the platen; means for winding up said spring mechanism in the course of displacing the platen to its inoperative position at the termination of the forward travel of the support; a lost-motion connection in the winding-up means; and means for reducing the lost motion as the support approaches the platen.

7. Apparatus according to claim 2, having the catch arranged to hold the support in its forward position, and an operator's control for disconnecting the loading means and for releasing the catch.

8. Manifolding apparatus of the kind referred to, having spring-return mechanism for retracting the trolley, movable lengthwise of the trolley track and including a connecting member through which load is applied to the spring, winding-up means for the spring-return mechanism which means includes a driving member normally spaced from the connecting member but movable lengthwise of the track, on operation of the winding-up means, into contact with the connecting member to move the latter and to load the spring, an adjustable back-stop for the trolley, adjustment means for said stop, a cord and pulley system connecting the adjustment means, the trolley, and the spring-return mechanism, a rack extending lengthwise of the track, a pawl on the trolley for engaging the rack and for preventing retraction of the trolley, and release means for releasing said pawl when the spring-return mechanism has been wound up to a predetermined extent.

CLAUDE WELLINGTON BRUMHILL.
